ALBERT SCHINKEZ, OF GRAND HAVEN, MICHIGAN, ASSIGNOR TO WILLIAM H. KELLER,
INC., OF GRAND HAVEN, MICHIGAN, A CORPORATION OF MICHIGAN.

ROTARY PISTON DRILL.

Application filed March 27, 1920. Serial No. 369,180.

To all whom it may concern:

Be it known that I, ALBERT SCHINKEZ, an Austrian subject, residing at Grand Haven, in the county of Ottawa and State of Michigan, have invented certain new and useful Improvements in Rotary Piston Drills, of which the following is a specification.

The invention relates to a pressure fluid actuated tool such, for example, as a pneumatic drill; and the general object of the invention is to provide a pneumatic drill of a practical and efficient character wherein pressure fluid is employed in such a manner as to act directly upon a rotary element to rotate the same.

A further aim of the invention is to provide a tool of the character stated in which the operating mechanism is advantageously arranged within a casing of convenient size and shape, providing a tool of relatively light weight and of high efficiency in operation.

The objects of the invention thus generally stated together with other and ancillary advantages may be attained by the construction and arrangement illustrated in the accompanying drawings forming part hereof in which Figure 1 is a longitudinal central sectional view through a tool embodying the features of my invention. Fig. 2 is a fragmentary sectional view somewhat similar to Fig. 1 but showing the operating mechanism in elevation. Fig. 3 is a transverse sectional view taken on line 3—3 of Fig. 1. Fig. 4 is a transverse section taken on line 4—4 of Fig. 1. Fig. 5 is a transverse section taken on line 5—5 of Fig. 1. Fig. 6 is a transverse section taken on line 6—6 of Fig. 1. Fig. 7 is a sectional view taken in the plane of line 7—7 of Fig. 1 and showing the pressure fluid inlet and exhaust ports. Fig. 8 is a section taken on line 8 of Fig. 1 showing a detail of construction.

The tool comprises, generally, a casing or barrel 1 having a handle 2 on its rear end and a tool spindle 3 rotatably mounted at its forward end in a journal 4. The handle comprises the usual hand portion 2^a and forward portion 2^b, and is provided with a passageway 5 for pressure-fluid, which passageway is manually controlled

by suitable valve means 6 of ordinary construction. 7 designates a rotatable element mounted in the forward end of the casing and operatively connected with the tool spindle and also with a series of pistons 8 operable in a series of cylinders provided by an element 9 which is rotatably mounted in the rear end of the barrel. Pressure-fluid is admitted successively to the cylinders of said element 9 by way of a distributor comprising an annular rotatable element 10 rigid with the element 9 and provided with a series of passages establishing communication between the respective cylinders and with two ports 11 and 12 provided in a stationary element formed by a member 13. The latter is mounted in the rear end of the barrel and is adapted to control such communication between the ports 11 and 12 and the cylinders whereby to cause the pistons to act upon the element 7 and impart a rotary motion thereto, the cylinders and the rotatable section of the distributor rotating with the element to effect the distribution of the pressure-fluid.

The casing or barrel 1 is made in two sections 1^a and 1^b secured together by means of bolts 14 entered through the forward end wall of the section 1^b and screw-threaded into lugs 15 provided upon the inner periphery of the section 1^a at the forward end thereof. Preferably the section 1^a and the handle are formed integrally while the section 1^b carries the journal 4 for the drill spindle 3. Said spindle has fixed upon its rear end, within the barrel, a bevel pinion 15 which meshes with a bevel pinion 16 rigid with the rotatable element 7. Said element is in the form of a plate or disk having a tubular sleeve 17 journaled upon a stem or post 18 fixed in the forward wall of the barrel. Said post is herein shown as entered at its forward end through a bearing or boss 19 and clamped in position by means of a nut 20; and friction bearings 21 and 22 of suitable construction are preferably provided between the sleeve and collars 18^a and 18^b at opposite ends of the stem, the collar 18^a being formed integral with the stem and the latter secured thereon by means of a nut 20^a.

As shown clearly in Figs. 1 and 2, the stem 18 is disposed diagonally of the barrel

and the element 7 at the forward end of its bearing sleeve 17 is inclined from the vertical with its center located substantially centrally of the barrel. The connections between the element 7 and the pistons 8 comprise a plurality of pitmen 23 universally connected at their opposite ends to the element and the pistons respectively. To this end the element 7 is provided in its forward face with a series of sockets 24 for receiving balls 25 provided on the forward ends of the pitmen. Upon the forward face of the element is secured a plate 26 having apertures of diameters somewhat less than the balls 25 and serving to retain the balls in position in their sockets. Similarly the opposite ends of the pitmen 23 are provided with balls 27 fitting in sockets 28 provided in central bearing blocks 29 formed integral with the pistons; and spring clips 30 (Fig. 8) entered in grooves 31 near the forward ends of said sockets serve to retain the balls in position therein.

The element 9 is adapted to provide cylinders for the pistons 8, herein four in number. Preferably said element is formed from a single piece of metal in which are formed cylinders 32, 32^a, 32^b and 32^c. It will be understood that any suitable or preferred number of cylinders may be employed. For the purpose of rotatably mounting said element 9 in the barrel 1, the latter has a central bearing stud or journal 33 disposed axially of the barrel. Said stud 33 may be formed integral with the member 13 mounted in the rear end of the casing in a manner to be later set forth. The rear end of the element 9 bears against an annular shoulder 34 formed at the rear end of the journal 33, and a screw 35 entered in the forward end of the journal so as to co-operate with the shoulder 34 in holding the element upon the journal. To further provide a bearing for the rear end of the element 9 and to receive the rearward thrust in the operation of the tool, suitable anti-friction bearings 36 are provided between the rear wall of the element and the rear wall of the barrel. In order that the elements 7 and 9 shall be retained in proper relative positions circumferentially of the barrel as they rotate in the operation of the tool, a pair of pins 37 are employed to serve as an additional connection between the element 7 and the element 9. Said pins, at their rear ends, are fixed in substantially diametrically opposite sides of the element 9, as shown in Fig. 3, and project forwardly in the barrel, their forward ends passing loosely through notches 38 provided in the plate 26 upon the forward face of the element 7, the element 7 being cut away as shown in Fig. 4 on diametrically opposite sides for the sake of lightness and simplicity in construction. The notches 38 are made

sufficiently large to permit of the relative movement between the pins and the plate 26 on the forward face of the element 7 in the rotation of such parts.

The element 10 which forms together with the member 13 the distributor for the pressure-fluid, comprises a tubular member 37^a rigid with the element 9 and an inner sleeve 38 fixed within said tubular member 37^a and rotatably mounted upon the forward end of the member 13. In said member 37^a and the sleeve 38 are formed the passages for the pressure-fluid. Said passages comprise longitudinally extending grooves 39, 39^a, 39^b and 39^c formed in the member 37^a and opening at their forward ends into the rear ends of the cylinders 32, 32^a, 32^b and 32^c, respectively, and communicating with the interior of the sleeve 38 by means of slots 40, 40^a, 40^b and 40^c, formed in the sleeve adjacent said grooves (Figs. 1 and 5). For controlling the flow of pressure-fluid through said passages, the member 13 at its forward end is shaped to provide a pair of diametrically opposite valve members 41 and 42 (Fig. 5), 90 opposite sides of the member between said valve members being reduced to a diameter somewhat less than the internal diameter of the sleeve 38 to form oppositely disposed chambers 11^a and 12^a. Pressure-fluid is adapted to enter the chamber 11^a, which constitutes an inlet chamber, by way of the port 11 which is formed in the rear portion of the member 13 and communicates with the passage 5, as shown in Fig. 7. The opposite or exhaust chamber 12^a communicates at its rear end with the exhaust port 12 formed in the side of the member 13 opposite the port 11 and communicating at its rear end with an exhaust passage 43 opening to the atmosphere. The member 13 at its rear end is pressed into a socket 44 in the forward end of the handle 2 so as to be firmly held in position therein. To further secure the member 13 in position, it may be provided with a rearwardly projecting stud 45 passing through an aperture in the forward portion 2^b of the handle and having a clamping nut 46 thereon.

The operation of the tool is as follows: 115 Assuming the parts to be in the position shown in the drawings, reference being had to Figs. 1 and 5 particularly, pressure-fluid flowing from the passageway 5 in the handle enters by way of the port 11 the inlet chamber 11^a with the valve portions 41 and 42 of the member 13 closing diametrically opposite slots 40 and 40^c. In this position of the parts pressure-fluid passes through slot 40^a into groove 39^a and thence into the rear end of the cylinder 32^a, driving the piston 8 therein forwardly and exerting pressure upon the element 7 through the medium of its pitman 23. At the same time pressure-fluid is exhausting from cylinder 32^c by way 120 125 130

of passage 39^c and slot 40^c to the opposite side of the member 13, or into chamber 12^a, whence it is conducted by way of the exhaust pasageway 12 to the exhaust port 43 in the handle. Movement is imparted to the element 7 by the pressure of the piston in cylinder 32^a, owing to the inclination of such element, and in such movement the element, through the medium of the pins 37 and pitmen 23, causes the element 9 to revolve and with it the element 10 of the distributor. The movement being in a clockwise direction (Fig. 5) the slot 40 is carried from beneath the valve portion 41 so that pressure-fluid is now also admitted by way of the passageway 39 to the cylinder 32. Pressure-fluid continues to act upon the piston in cylinder 32^a until the slot 40^a moves beneath valve portion 42, and is successively admitted to cylinders 32^c and 32^b, thus imparting a rotary motion to the element 7. In such movement, also, pressure-fluid is exhausting from cylinders 32^c and 32^b, and successively, in the rotation of the element 9, from the cylinders 32^a and 32. It will thus be seen that pressure-fluid is successively admitted to the cylinders in the rotation of the element 9 and is also successively exhausted from the cylinders, at least one, and for the greater portion of the movement, two of the cylinders receiving charges of pressure-fluid while the other one or two of the cylinders are exhausting. By this arrangement the two rearmost, herein the two lowermost pistons are driven forwardly to impart a rotary movement to the element 7 while the two uppermost or foremost pistons are free to move rearwardly. Moreover, it will be noted that when one only of the pistons is receiving a charge of pressure-fluid such piston is positioned so as to exert a maximum amount of effective force upon the element 7 so that the element 7 is at no time at dead center.

It will be seen that I have provided a tool of extreme simplicity in which pressure-fluid acts directly upon an element to impart rotary movement thereto. The parts of the tool are compactly arranged, and the tool as a whole is of light weight and of minimum size, permitting of its use in restricted places. The location of the tool spindle 3 near the periphery of the tool is especially advantageous in permitting access to corners and like places.

While I have herein illustrated and described the invention with considerable particularity, it will be understood that the invention is not to be limited, in the interpretation of the appended claims, except as may be necessitated by the prior art, for many changes in construction and arrange-

ment may doubtless be made without departing from the spirit and scope of the invention.

65

I claim as my invention:

1. A pressure-fluid-actuated tool comprising, in combination, a casing having a forward section and a rear section, the rear section having a handle rigid therewith and the forward section having a forwardly projecting journal bearing, said handle having a valve controlled air passage therein, valve means mounted in the rear section and adapted to control the flow of pressure fluid from said passage, said valve means including a stationary member having rigid therewith a journal extending forwardly into the rear section of the casing substantially coaxially thereof, a plurality of cylinders rotatable as a unit upon said journal, said valve means being adapted to control the flow of pressure fluid to and from said cylinders, pistons in said cylinders, an inclined disk mounted in the forward casing section to rotate on an axis intersecting the axis of the cylinder unit, means operatively connecting said pistons with said inclined member whereby in the reciprocation of the pistons to cause the said member to rotate, and a shaft journaled in the bearing in the forward casing section and having a gearing connection with said inclined member.

2. A pressure fluid actuated tool comprising, in combination, a cylindrical casing, a stud disposed coaxially of said casing and projecting forwardly therein, a plurality of cylinders arranged circumferentially about said stud to be supported thereby and each having a piston therein, valve means for controlling the flow of pressure fluid to and from said cylinders including a stationary member mounted in the rear wall of the casing, an inclined member operatively connected with said pistons and mounted in the forward end of said casing to rotate on an axis extending substantially diagonally of the casing, said inclined member having an elongated tubular portion and said casing having mounted therein at one side of its axis a second stud providing a support for said elongated portion of the inclined member, a shaft mounted in the forward end of the casing upon the side of the axis opposite said second stud but parallel with the axis of the casing, and a pair of bevel gears rigid with the inclined member and with said shaft respectively whereby rotary motion imparted to the inclined member is transmitted to the shaft.

In testimony whereof, I have hereunto set my hand.

ALBERT SCHINKEZ.
